CAMOUFLAGE STRUCTURE

Robert P. Moran, West Orange, N. J., assignor
to Western Electric Company, Incorporated,
New York, N. Y., a corporation of New York

Application December 8, 1942, Serial No. 468,392

11 Claims. (Cl. 135—5)

This invention relates to camouflage structures, particularly structures for covering open areas.

Numerous steps have been taken in defense areas to eliminate attraction thereto from the air, particularly at night, including the painting of windows to eliminate reflections. As a further protective step against attraction to such areas, it has been considered advantageous to provide a covering for parking areas, to conceal the large number of cars usually present there and to eliminate any directing aid, to an adversary, which might be given through reflections from the cars in such areas.

An object of the invention is to provide a camouflage structure which is particularly adaptable to parking areas.

With this and other objects in view, the invention comprises a camouflage structure, including a plurality of poles erected in rows at spaced positions about a selected area, saddles mounted upon the poles, anchors for catenary cables, cables extending from the anchors over the saddles in various directions, and a disguising material secured to the cables.

Other objects and advantages will be apparent from the following detailed description when considered in conjunction with the accompanying drawings, wherein

Fig. 1 is a fragmentary schematic top plan view of the camouflage structure completed to the stringing of the catenary cables;

Fig. 2 is a side elevational view illustrating the elevation of a pole at the side of the area and the anchoring means associated therewith;

Fig. 3 is a fragmentary top plan view of the structure shown in Fig. 2;

Fig. 4 is a fragmentary side elevational view illustrating the erection of a pole and the location of the footing structure therefor;

Fig. 5 is a horizontal sectional view taken along the line 5—5 of Fig. 4;

Fig. 6 is an enlarged fragmentary detail view of one of the poles illustrating the attachment of the anchoring cable thereto;

Fig. 7 is a perspective view of one of the saddles mounted upon a pole;

Fig. 8 is a side elevational view of the structure shown in Fig. 7, illustrating the saddle and the clamping plate therefor;

Fig. 9 is a side elevational view of one section of the camouflage structure at the completion of the supporting grill for the disguising material;

Fig. 10 is a fragmentary top plan view of the supporting grill structure illustrating the manner in which it is formed;

Fig. 11 is a front elevational view of one of the supporting hangers extending from a catenary cable, to support the grill and its disguising material;

Fig. 12 is a fragmentary sectional view taken along the line 12—12 of Fig. 11;

Fig. 13 is a fragmentary sectional view taken along the line 13—13 of Fig. 11;

Fig. 14 is a schematic side elevational view of the camouflage structure illustrating the elevation of the supporting grill and its disguising material for mounting on the hangers, and

Fig. 15 is a fragmentary detail view illustrating the manner of elevating the supporting grill and disguising material for mounting on the hangers.

For the purpose of illustrating the invention, let it be assumed that a parking area of considerable size is to be covered with the camouflage structure. The first step to be taken is to determine the nature of the ground area and marking pole locations at definite spaced positions about the area. In the present embodiment it has been determined that poles constructed, for example, of southern yellow pine and having top-dimensions of approximately thirty-eight inches (38") in circumference, would be of sufficient strength to support the remaining structure. The holes for the poles are dug in the ground in the present instance at fifty-five (55) foot centers, these holes being made only sufficiently large for the positioning of the poles therein, leaving undisturbed the natural ground structure about the poles for lateral support of the pole. It is also important that the holes be dug only to the given depth and that the bottom of the holes be as truly horizontal, as is possible, to provide a solid base for the lower ends of the poles. This eliminates settling of the poles and provides a firm foundation therefor.

In Figs. 2 to 5 inclusive, the mounting of the poles is illustrated. In Figs. 2 and 4, for example, it will be noted that a pole 10 is lowered into a hole 11 a given distance, the upper end of the pole extending another given distance about the ground level 12.

In areas where the ground structure is sufficiently solid for the poles to carry the necessary weight without settling, it may not be necessary for footings to be added, yet it has

been found that in numerous manufacturing areas the ground structure is not of a type which would give a satisfactory support to the poles under such conditions. In such instances the addition of footings, indicated at 14, is advisable. The 55 footings 14 are shown in detail in Figs. 4 and 5.

In these figures it will be apparent that a plurality of surface boards 15, positioned upon opposite sides of the pole 10 in a horizontal plane, is secured in position by parallel beams 16 disposed upon opposite sides of the pole and secured thereto through the aid of bolts 17. Other transverse beams 18 lay across the beams 16 and are similarly secured to the pole 10 through the aid of bolts 19. The beams 16 and 18 extend into recesses in the pole to receive any load on the pole and distribute it to the boards 15 so that the footing may share in supporting the load. This completes the footing structure for the poles which may be assembled prior to the erection of the poles but preferably thereafter. Prior to the mounting of the footing 14, a recess 20 is formed in the ground about the pole, care being taken not to disturb the ground beyond the depth desired so that the boards 15 may rest in the recess, their upper surfaces being flush with the surface of the ground.

On the outer poles, that is the poles located at the edges of the area, guy hooks 22 are suitably mounted upon the outer surfaces of the poles at given heights from the ground level, guy plates 23 being mounted at slightly lower positions upon the opposite or inner sides of the poles. Mounted at a given level on the outer poles, are anchoring plates 24 having hook-like retaining lugs 25 for receiving and holding in clamped position the marginal cable of the grill structure shown in Fig. 10. The positions of the plates 24 may vary depending upon the location desired for the supporting grill shown in Fig. 10.

Attention is now directed to a saddle 28 (Figs. 7 and 8) which is a hollow casting of a size sufficient to receive the end of the pole 10 and to rest firmly thereon. The upper structure of the saddle includes a plurality of cable supporting grooves extending in transverse directions and disposed at different levels to receive the catenary cables. The first or lowermost groove is indicated at 30 and extends through the upper structure of the saddle, indicated at 31. The next groove is indicated at 32, extending at a forty-five degree (45°) angle across the groove 30 and is therefore of two aligned parts as shown in Fig. 7. The next groove is indicated at 33, this groove extending at right angles across the groove 32 and positioned thereabove. Finally, a groove 34, positioned in the end pieces of the structure 31 and extending at right angles to the groove 30, is positioned above all other grooves. With this arrangement catenary cables may be located in their respective grooves, crossing each other at different levels so that the cables may rest upon each other at the crossing points, yet be supported by the saddle structure in their respective grooves. It will be noted that the end pieces or members of the upper structure have threaded apertures 36 which are adapted to receive screws 37, for the securing of a clamping plate 38 over the cables supported by the saddle.

The structure of the poles, the erection thereof, together with the other structures associated with the poles, having been described, attention is now directed to the anchoring means which is illustrated in Figs. 1, 2 and 3. The poles, as described, are capable of supporting any vertical thrust which may be applied thereto through the weight of the structure and other loads such as wind, snow, rain or ice, yet due to the lateral pull on the poles through such circumstances, anchoring means is necessary to support the poles against this added force. The anchoring means

consists mainly of a log 40 of a given length, for example, twenty-two feet (22'), provided with apertures at desired positions and at selected angles to receive anchoring rods 41 and a guy rod 42. The rods 41 and 42 may be passed through their apertures and secured in place by suitable means, such as threaded nuts 43, on the threaded ends of the rods, and suitable plates 44 are provided between the nuts to distribute the loads on the log. The log 40 with its rods 41 and 42 is disposed in a trench 45 formed in the ground as illustrated in Fig. 2. The trench 45 is located a given distance from its respective pole 10 as illustrated in Figs. 1 and 2, particular care being taken during the forming of the trench to leave an undisturbed wall against which the log may rest and a pocket 46, at the bottom of the trench, to receive the log. Prior to the time the anchoring log may be lowered into the trench, lateral grooves 47 must be provided for receiving the rods 41 and 42. Here again care must be taken to provide the necessary grooves in the ground for the rods, endeavoring not to disturb the adjacent solid wall of the trench against which the anchor log rests. When this has been accomplished the trench is filled by alternate filling and tamping steps.

The next step is the stringing of the catenary cables. These cables are to be of suitably strong structures, for example five-eighths of an inch (5/8") diameter stranded galvanized cable, as it is from these cables that the grill and disguising material are suspended. By viewing Fig. 1 for the moment, let it be understood that the saddles 28 are positioned in a like manner on each pole, for example, so that the groove 30 will extend longitudinally or lengthwise of the sheet and the groove 34 will extend laterally or across the sheet. All of the longitudinal cables will therefore be laid first, connecting their beginning ends to their respective rods at one end, for example the bottom of Fig. 1, and then stringing the cables along their respective rows of poles, coming to rest in the grooves 30 of each of their saddles and finally securing the remaining ends of these cables to the rods 41 at the opposite or upper end of Fig. 1. It is important in stringing these cables, that the ends of the cables from the rods 41 to the saddles of the first and last poles be taut and that the cable between each saddle be accurately sagged to given dimensions as illustrated in Figs. 9 and 14. In this manner a sag is originally placed in the cables to decrease the pull on the cables. After the stringing of the first group of catenary cables, these cables, bearing reference numerals 54, cables 55 are strung in a similar manner, extending from their respective rods 41 at one side of the structure and extending through the grooves 32 of the saddles on their respective poles, and finally secured to the rods 41 at the opposite sides. These cables are strung in a similar manner to the stringing of the cables 54, they being taut between their rods 41 and the saddles of the adjacent poles and provided with an accurate sag between each pole. In a similar manner cables 56 are strung, passing through grooves 33 of their respective saddles and having their ends connected to their respective rods 41. Cables 57 are then strung, these cables extending from their respective rods 41 and laying in the grooves 34 of the saddles over the poles which they pass, and are also provided with an accurate sag between the poles. After the catenary cables have been strung, the clamping plates 38 will be disposed in place on each saddle and tightened to hold the adjacent portions of the cables in place.

It has been described that during the stringing of the catenary cables 54 to 57 inclusive, their ends are drawn taut from marginal poles to their anchor rods. However, there is an additional drawing of the ends of the catenary cables after the mounting of the clamping plates 58, to cause outward deflection of the marginal poles to allow for settling or final positioning of the anchor logs associated therewith after the catenary cables have been subjected to the weight of the supporting grill, disguising material and other possible material such as snow, water or the like. This outer deflection of the marginal poles will remove some of the sag in the adjacent cable portions, but after these cable portions have been subjected to the aforementioned additional weight and the anchor logs have settled into position, these cable portions will again assume the original sag. This further adjustment of the cables between their anchor rods and marginal poles may be accomplished through the aid of the clamps 59 or, if desired, other means such as turnbuckles may be employed. After this step has been completed, that is after the final stringing of the catenary cables and the deflection of the marginal poles, guy wires or cables 60, having their lower ends connected to their respective anchor rods 42, may have their upper ends passed about their respective marginal poles as shown in Figs. 2 and 6 and secured through the aid of clamps 61. It will be noted, by viewing Fig. 6, that the upper portion of the cable 60 passes around the plate 23, lies in the hook 22, and continues around the pole and plate a second time, and is finally secured to the adjacent portion of the cable by the aid of the clamp 61. These guy wires are therefore secured to the marginal poles after the poles have been deflected, and thus provide an additional outer support for each marginal pole adjacent the anchoring plates 24, where the supporting grill is to be mounted. These guy wires thus counteract the opposing pull of the supporting grill on the marginal poles and eliminate possible inward deflection of the poles as a result thereof.

The next step is the mounting of the hangers shown specifically in Figs. 9, 11, 12 and 13. The hangers, indicated generally at 60, have clamps 61 formed of two parts, as shown in Fig. 12, with groove portions adapted to receive any of the catenary cables, for example one of the cables 54, at their upper portions and grooved also at their lower portions to receive U-shaped suspending members 62, there being a single member 62 for each hanger. The members of the clamps 61 are provided with a bolt 63 to draw the members toward each other into clamping engagement with the suspending members and the cable upon which they are mounted. Referring to the hanger shown, it will be noted that the legs of the suspending member 62 have rounded ends 64 with outwardly projecting lugs adapted for the resting of a retaining plate 65 and a supporting lug 66, the latter being recessed at the side walls thereof to receive the legs of the suspending member and grooved, at 67, for a purpose hereinafter described. It will be noted, by viewing Fig. 13, that the groove 67 extends diagonally across the upper surface of the supporting lug 66. The purpose of the retaining plate 65 is to hold the legs of the suspending member 62 in supporting engagement relative to the lug 66.

In covering a large area wherein there are numerous sections of the camouflage structure, there will be a multiplicity of hangers 60 which

will be identical in structure excepting the length of the suspending member 62, which will vary, as illustrated in Fig. 9, to compensate for the sagging portions of the catenary cables between the poles. As the extent of the sag in all portions of the cable is the same and predetermined, the length of the suspending member 62 may be known and the desired number of hangers and the different lengths of suspending members may be known prior to the erection of the structure. In the present embodiment it will be necessary for only five different lengths of suspending members. With these different lengths the clamps 61 and the suspending members of the desired lengths are mounted at different spaced positions upon the catenary cables 54 to 57 inclusive, as shown in Fig. 9. Here attention is directed to the fact that the lower ends of the suspended members 62 on each cable portion are not in a common plane but lie in an arc to give a predetermined camber to the supporting grill.

The next step includes the forming of the supporting grill shown in Fig. 10. With the assistance of Fig. 1 and the understanding that from this illustration the structure may be composed of numerous sections of four poles forming squares, then a more complete understanding of the grill structure shown in Fig. 10 may be determined. An outer marginal cable 70 may be started at any desired position and extended about the entire area touching the outer surface of each marginal pole, as illustrated in Fig. 10, and continued until the cable has extended about the entire area. In laying this cable, it is given a definite sag between each pole, and after the cable is accurately located the ends thereof may be secured together in an overlapping arrangement and secured together by a clamp, similar to the clamp 61 shown in Fig. 6. Smaller, yet sufficiently durable, cables or wires 71 have their beginning ends clamped, as at 72, to given spaced positions on the marginal cable 70 and are then extended the full length of the structure, where their opposite ends are clamped in a similar manner to the opposite portions of the marginal cable. The clamps 72 are substantially identical in structure to the clamp 61 shown in Figs. 11 and 12. The stringing of the cable 71 is continued until all of the longitudinal cables for the full width of the grill have been strung and clamped to the marginal cable. The cables 71 of the outer group are spaced further apart than the central group of cables, the purpose of the latter being to reinforce the center structures of each section, where the greatest weight may exist, the portion farthest from the supporting means, namely the poles. After the longitudinal cables 71 have been laid and secured in place, transverse cables or wires 73 may, in a similar manner, have their beginning ends clamped, as at 74, to one side of the marginal cable 70, laid across the longitudinal cable 71 the full width of the grill structure, and have their opposite ends clamped to the adjacent portions of the marginal cable. Here again the cables of the central group are more closely spaced, to add strength to the central area of the grill structure at each section. The clamps 74 are also substantially identical to the clamps 61 of the hangers. At all or selected junctures of the cables 71 and 73, ties 75 may be made of suitable wire to hold the cables against movement out of their original positions and to complete the grill structure. This entire structure is formed on the ground or as close to the ground as the footings 14 will permit, and

after the grill structure has been completed, a disguising material, such as a garnished mesh 78 (Fig. 11), of a suitable commercially known type of structure may be laid upon the supporting grill, to completely cover the grill, if desired, or to leave openings for the escapement of exhaust gases or to add to the camouflage effect. The garnished mesh usually includes materials of various colors and shades, supported by a wire mesh, which structure may be secured in any desired manner to the cables of the grill.

The next step includes hoisting of the supporting grill with the garnished mesh attachment to the hangers 60. Any suitable means may be employed for this purpose, sets of blocks and tackles 78 being illustrated in the present embodiment to carry out the raising of the grill structure into position, it being remembered that the marginal cable 70 extends about outer or marginal poles and with the aid of the block and tackle removably connected to the poles as at 79, the grill structure may be readily raised into position. It is preferable to start raising the grill at one corner of the area, that is one corner of the grill structure, using, for example, three sets of blocks and tackles being operated, one from a corner pole and the others from the two next adjacent poles. In this manner the grill structure may be raised, beginning at the selected corner and assisted by the next adjacent lifting means until the selected corner has been raised to the proper height, at which time the suspending members 62 of the adjacent hanger 60 shown schematically in Fig. 14 may be attached to the adjacent portions of the grill. This is accomplished by forcing the legs of the suspending members 62 through the garnished mesh (Fig. 11) and then assembling the members 65 and 66 on the ends of the suspending members beneath the grill and preferably at the juncture of the cables 71 and 73. In this manner the mounting of each lug 66, assisted by its retaining plate 65, will allow one of the cables 71 to rest in the groove 67 thereof, the adjacent cable 73 resting upon the cable 71, and both cables are positioned between the legs of the suspending member and supported thus by the hanger. This process is continued, gradually elevating the grill structure from the selected corner, and, as the grill structure is elevated, it is secured to the hangers 60. This is continued until the entire supporting grill with its garnished mesh is brought into position and secured to all of the hangers 60. Due to the arcuate arrangement of the lower ends of the suspending members 62 of the hangers, the supporting grill and garnished mesh are cambered at each section.

In reviewing the camouflage structure and the steps of the method of erecting it, there exists first the selection of poles 10 of approximately the same diameter and of the same length, these poles being provided with footings of the structure shown in Figs. 4 and 5 and erected in carefully prepared holes, the poles being erected preferably prior to the assembling of the footings so that the holes may be carefully filled and the filled earth tamped in place. The footings are thus mounted on the poles and lie in the recesses in the ground provided therefor, so that the upper surfaces of the board 16 lie flush with the ground 12. The saddles 28 are then mounted upon the poles, with like grooves thereof extending in like directions, so that all portions of like catenary cables passing over the poles will lie in the identical planes. With this arrangement of the saddles and cables the total weight

presented at the poles through the catenary cables is directly on the top of the poles, centered there through the crossing of the catenary cables over these areas.

5 However, prior to the positioning of the catenary cables, the anchor logs are prepared and located with their rods in their respective trenches. Through the aid of the anchor logs, the efficiency of the anchoring means is distributed throughout a large area and not limited to individual areas for each rod, which would exist if the rods were anchored individually in concrete. After the laying of the catenary cables the marginal poles are deflected outwardly given 10 distances to counteract inner deflections which they will receive after the mounting of the supporting grill and the garnished mesh and to allow for settling of the anchor logs.

At this time, assuming that the catenary cables 20 have been laid and the guy wires secured in place, the hangers 60 are mounted in their given positions with the selected lengths of suspending members 62, so that the lower ends thereof on each cable portion in each section (of four poles) 25 will lie in like arcs. After this has been completed, the supporting grill shown in Fig. 10 may be formed provided with the selected garnished mesh, and then elevated into position and attached at the numerous locations of the hangers 60. When in this position the marginal cable 30 will lie in the anchoring plates 24, after which the retaining lugs 25 thereof may be bent about the marginal cable to secure it in place.

This completes the camouflage structure, which 35 may cover any area regardless of its size, leaving sections between groups of the poles to provide sufficient space for the parking of cars, trucks or the like. Furthermore, the supporting structure is suitably mounted at a sufficient 40 height above the ground for the free travel of the vehicles into and out of parking position in the sections. All that is apparent above the garnished mesh at close range are the upper ends of the poles, the catenary cables and the upper 45 portions of the hangers, and these, if so desired, may be painted, colored or garnished in a suitable manner to blend with the garnished mesh. Furthermore, these upper structures, without coloring or garnishing, would not be apparent 50 from the average height of an aeroplane, as they would blend into the garnished mesh. The same is true of the anchoring rods and the adjacent cables connected thereto.

This provides a structure which is free of connecting joints which would be necessary, for example, if the supporting grill were formed of commercially known mesh material such as wire fencing, as such materials are not prepared in lengths desired for such areas, and the weight 55 which such structure might have to support in addition to its own weight would be too great for the joints thereof. In the present embodiment each cable of the supporting mesh extends the full width and/or the full length of the grill, there being no joints in any of these cables. The same is true of the catenary cables. Therefore, with the solid cable structure of the grill it is capable of supporting not only its own weight, that of the garnished mesh, but any 60 added weight such as snow, wind, rain or ice which may be deposited or formed thereon during a winter season.

Although specific improvements of the invention have been shown and described, it will be understood that they are but illustrative and

that various modifications may be made therein without departing from the scope and spirit of this invention as defined by the appended claims.

What is claimed is:

1. A camouflage structure for a given area comprising a plurality of poles erected in rows at spaced positions across the area, cable anchors disposed adjacent and beyond the ends of the rows of poles, cables strung in different directions over the tops of the poles and having their ends secured to their respective anchors, and a material for covering and camouflaging said area secured to the cables. 5
2. A camouflage structure for a given area comprising a plurality of poles erected in rows at spaced positions across the area, cable anchors disposed adjacent and beyond the ends of the rows of poles, cables strung in different directions over the tops of the poles and having their ends secured to their respective anchors, means mounted on the poles to individually support the adjacent portions of the cables, and a material for covering and camouflaging said area secured to the cables. 10
3. A camouflage structure for a given area comprising a plurality of poles erected in rows at spaced positions across the area, cable anchors disposed adjacent and beyond the ends of the rows of poles, cables strung in different directions over the tops of the poles and having their ends secured to their respective anchors, a supporting grill for a material for camouflaging said area, means to secure the grill to the cables, means to secure the grill to the poles at given positions, and means to support the poles against deflection by the grill. 15
4. A camouflage structure for a given area comprising a plurality of poles erected in rows at spaced positions across the area, cable anchors disposed adjacent and beyond the ends of the rows of poles, cables strung in different directions over the tops of the poles with like sags in the cable portions between the poles, means to secure the cables to the poles, cable tension means associated with the cables and cable anchor, and a material for camouflaging said area secured to the cables. 20
5. A camouflage structure for a given area comprising a plurality of poles erected in rows at spaced positions across the area, cable anchors disposed adjacent and beyond the ends of the rows of poles, cables strung in different directions over the tops of the poles and having their ends secured to their respective anchors, a material for camouflaging said area secured to the cables, and vertical pole axis supporting means. 25
6. A camouflage structure for a given area comprising a plurality of poles erected in rows at spaced positions across the area, cable anchors disposed adjacent and beyond the ends of the rows of poles, cables strung in different directions over the tops of the poles and having their ends secured to their respective anchors, saddles severally mounted upon the poles, each to receive 30
- and support the adjacent portions of the various cables extending thereover, and a material for covering and camouflaging said area secured to the cables. 35
7. A camouflage structure for a given area comprising a plurality of poles erected in rows at spaced positions across the area, cable anchors disposed adjacent and beyond the ends of the rows of poles, cables strung in different directions over the tops of the poles and having their ends secured to their respective anchors, saddles having grooves therein lying substantially in the directions of the adjacent cable portions, severally mounted upon the poles each to receive the said cable portions, and a material for camouflaging said area secured to the cables. 40
8. A camouflage structure for a given area comprising a plurality of poles erected in rows at spaced positions across the area, cable anchors disposed adjacent and beyond the ends of the rows of poles, cables strung in different directions over the tops of the poles and having their ends secured to their respective anchors, saddles having grooves therein lying at different levels and substantially in the directions of the adjacent cable portions, severally mounted upon the poles each to receive the associated cable portions in the grooves, and a disguising material for camouflaging said area secured to the cables. 45
9. A camouflage structure for a given area comprising a plurality of poles erected in rows at spaced positions across the area, cable anchors disposed adjacent and beyond the ends of the rows of poles, cables strung in different directions over the tops of the poles and having their ends secured to their respective anchors, saddles having grooves therein lying at different levels and substantially in the directions of the adjacent cable portions, severally mounted upon the poles each to receive the associated cable portions in the grooves, a material for camouflaging said area secured to the cables, and clamping plates secured to the saddles to hold the portions of the cables in the grooves thereof against displacement. 50
10. A camouflage structure for a given area comprising a plurality of poles erected in rows at spaced positions across the area, cables strung over the poles, a supporting grill for a material for covering and camouflaging said area, and means to secure the grill to the cable portions between the poles, said means being of selected lengths to camber the portions of the grill between the poles. 55
11. A camouflage structure for a given area comprising a plurality of poles erected in rows at spaced positions across the area, cables strung over the poles, a supporting grill for a material for camouflaging said area, and hangers of varying selected lengths for securing the grill to the cable portions between the poles to camber the portions of the grill between the poles. 60

ROBERT P. MORAN.
